UNITED STATES PATENT OFFICE.

KLEBER W. SMITH, OF FREEPORT, MAINE.

GASOLENE-DELIVERY TANK.

1,338,878.

Specification of Letters Patent.

Patented May 4, 1920.

Application filed August 3, 1917. Serial No. 184,230.

To all whom it may concern:

Be it known that I, KLEBER W. SMITH, a citizen of the United States of America, residing at Freeport, county of Cumberland, 5 State of Maine, have invented certain new and useful Improvements in Gasolene-Delivery Tanks, of which the following is a specification.

This invention relates to the dispensing 10 of gasolene and like commodities, and particularly to apparatus for supplying such liquid fuel as gasolene, kerosene or the like to automobilists as is the common practice at a garage or roadside.

15 The filling of a car tank from the ordinary pump has offered such opportunities for short measure and for inferior or unfit fuel that there has been almost a premium on rascality and a corresponding cheating 20 of the public both as to quantity and quality, so that the automobilists, when compelled to deal with a strange vender, if not actually cheated have been so in unpleasant apprehension of dishonesty. Likewise honest dealers have suffered from unfounded 25 suspicion and have frequently lost trade and even reputation owing to the manner in which the transaction was effected.

It is the object of my invention to 30 make it possible for the purchaser to actually see the commodity which he is purchasing and correspondingly for the vender to display the goods which he is delivering. I accomplish this by providing a trans- 35 parent intermediate tank so associated with the pump that when the desired amount of gasolene or other fuel is delivered into the tank it may not be surreptitiously withdrawn, tapped or fouled, but may be readily discharged into the tank of the automobile.

The construction and operation of my device will be more fully disclosed in the specification which follows. In the drawings I 45 have shown a form of apparatus well adapted to practical service and which well illustrates the principles involved in my invention. Throughout the specification and drawings like reference numerals are em- 50 ployed to indicate corresponding parts, and in the drawings:

The single figure is a partial vertical section of a supply outfit in accordance with my invention.

55 I have indicated at 1 a suitable head or casing within which is inclosed a pump P

of well known type. The pump connects at 2¹ with a fuel storage tank 2 and has a delivery 3¹ which may be provided at any desired point with a valve 3. Mounted upon 60 the head 1 is a plurality of spaced tubular supports 5 upon the upper ends of which a base 6 is mounted. The base 6 is formed with an annular shoulder 7 providing a seat for a container 8, there being preferably interposed between the base 6 and container 8 a rubber or other suitable gasket 9.

The container 8 may be provided with suitable graduations, as by etching, and has its discharge mouth disposed in registry 70 with a discharge passage 10 formed in the base 6 and to which passage a suitably controlled discharge pipe 11 is connected. In the embodiment shown, the control valve for the discharge pipe 11 is indicated at 12, 75 and the pipe 11 is connected by any suitable union 13 with a discharge hose or other suitable connection 14 which may be carried to the tank of the automobile.

Fixed within the head or casing 1 and ex- 80 tending through the supports 5 are tie rods 4. The rods 4 extend along the side of the container 8, terminating above the container and there being threaded, as indicated at 4¹, to receive a head or cover 15 for the container. The cover 15 has threaded thereinto a suitably formed pipe or coupling section 16 which, when the head 15 is in place upon the container, is adapted to be connected in any suitable manner, as by the union 17¹⁹ with the upper end of the pipe 3¹. The cover 15 may be provided with an air vent 18 and may be formed with a depending annular flange 19 adapted to engage the outer face of the container and center the cover 95 thereon. If desired, any suitable gasket 20 may be interposed between the cover and container. In addition to their function of connecting the base 6 and cover 15, the rods 4 also serve to protect the container 8 against 100. the breakage, constituting in effect an open frame work within which the frangible container is inclosed.

In the use of the device, the gasolene or other fluid is pumped from the tank 2 into 105 the pipe 3¹ from which it discharges into the transparent receptacle 8 and out therefrom through the hose or other connection 14 to the tank of the automobile.

It will thus be seen that I not only provide 100 against the possibility of the liquid being fouled, diluted or otherwise tampered with,

but insure that the purchaser may see not only the exact amount of fuel which he is contracting for, but also the condition of the fuel, all in an apparatus of simple and inexpensive construction.

Various modifications in the form and construction of my invention may obviously be resorted to if within the limits of the appended claims.

10 What I therefore claim and desire to secure by Letters Patent is:

1. Apparatus for visibly displaying measured quantities of gasolene or the like sold at a service station, comprising in combination with the usual storage tank and pump at the station, a combination fuel-measuring and display container supported adjacent the storage tank into which the gasolene is adapted to be pumped from the storage tank 20 and from which it is conducted to the gasolene tank of the motor vehicle, said container being transparent to display the fuel as it is pumped thereinto and having a series of fuel-measuring graduations, a supporting structure for said container including a plurality of spaced uprights between which the container is mounted intermediate of the ends thereof, and in inclosed protected relation and with its fuel-measuring graduations 30 freely observable through the spaces between said uprights, a feed connection leading from said storage tank into said container from above and a gravity discharge connection leading from said container from below.

2. In combination, a source of supply, a plurality of spaced uprights, a base mounted on said uprights and having an annular groove to receive the lower edge of a container and having a discharge opening communicating with the interior of the container, a transparent container supported on said base and inclosed within and protected by said uprights and having a series of graduations visibly exposed between said uprights, and a delivery connection from said source of supply to the interior of said container.

3. In combination, a source of supply, a plurality of spaced uprights, a base mounted on said uprights between the ends thereof and having an annular groove to receive the lower edge of a container and having a discharge opening communicating with the interior of the container, a transparent container supported on said base and inclosed within and protected by said uprights and having a series of graduations visibly exposed between said uprights, a cover for said container mounted on the upper ends of said uprights, and a delivery connection from said source of supply to the interior of said container.

In testimony whereof I affix my signature in presence of two witnesses.

KLEBER W. SMITH.
